Primary Examiner — Rhea Shields(74) *Attorney, Agent, or Firm* — Stephen C. Thomas**CLAIM**

The ornamental design for an eye exam apparatus, as shown and described.

DESCRIPTION

FIG. 1 is a front view of the eye exam apparatus, showing our new design;

FIG. 2 is a right side view thereof;

FIG. 3 is a left side view thereof;

FIG. 4 is a rear view thereof;

FIG. 5 is a top view thereof; and,

FIG. 6 is a perspective view thereof.

In the drawings, the broken lines are for the purpose of illustrating portions of the eye exam apparatus that form no part of the claimed design.
